(57) **CLAIM**

We claim, the ornamental design for network interface device bracket, as shown and described.

DESCRIPTION

FIG. 1 is a front, left, bottom perspective view of a network interface device bracket showing the claimed design;

FIG. 2 is front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines in the figures and the areas within the broken lines show portions of the network interface device bracket that form no part of the claimed design.

1 Claim, 7 Drawing Sheets
